UNITED STATES PATENT OFFICE.

DANIEL J. MURNANE, OF KIRKWOOD, MISSOURI, ASSIGNOR TO THE ST. LOUIS PLATE GLASS COMPANY, OF VALLEYPARK, MISSOURI, A CORPORATION OF MISSOURI.

GRINDING-DISK.

SPECIFICATION forming part of Letters Patent No. 747,208, dated December 15, 1903.

Application filed April 19, 1902. Serial No. 103,755. (No model.)

To all whom it may concern:

Be it known that I, DANIEL J. MURNANE, of Kirkwood, St. Louis county, Missouri, have invented a new and useful Grinding-Disk, of which the following is a full, clear, and exact description, reference being had to the accompanying drawings, forming part of this specification, in which—

Figure 1 shows in side elevation, partly in longitudinal section, a machine constructed in accordance with my invention and adapted for grinding plates or slabs of glass, stone, marble, &c. Fig. 2 is a similar view showing the application of my invention to a machine for pulverizing sand, &c. Fig. 3 shows on a larger scale, in side elevation, partly in vertical section, the mechanism which is preferably used for feeding the abrasive to the disk. Fig. 4 is a front elevation, partly broken away, of the grinding-disk. Fig. 5 is a plan view of the inner face of the disk used in the machine shown in Fig. 2. Fig. 6 is a plan view of the outer side of the disk of Fig. 1, showing the collar thereon in section. Fig. 7 is a face view of a modified construction of grinding-disk in which the grinding-surface is at the periphery; and Fig. 8 is a side view thereof, partly in section.

My machine is adapted to grind or polish the edges of plates and to perform other kinds of grinding or polishing or to pulverize abrasive material with great rapidity. It combines with a grinding-disk means for supplying the abrasive or the material to be pulverized to the surface of the disk during its rotation by feeding it thereto in such manner that the disk may be used when in a vertical or any other position.

In the drawings, Figs. 1, 3, and 4, 2 is the grinding-disk set in an upright plane, having a hub 3 and mounted on a rotary shaft or axis 4.

5 5 are passages which extend outwardly in the disk from the middle portion and communicate with passages 6, leading through the hub for the supply of abrasive material. The passages 5 are preferably formed by making the disk of a plate B, having its inner face grooved or recessed and covered by plates C, which may be held to the plate by

bolts 6 and are separated at intervals to constitute slots or openings 7, communicating with the passages 5. The slots 7 are inclined in the direction opposite to the direction of rotation of the disk. The passages 6 extend spirally in the hub to a stationary collar 8, which is set loosely and independently around the hub at the back of the disk. It is connected with a pipe or passage 9 for the introduction of the abrasive material, preferably mixed with water. When the abrasive is fed to the collar 8, the rotation of the hub will cause it to enter the spiral passages 6 and to be conveyed through the hub into the passages 5, through which it is distributed by the centrifugal force of rotation, and by reason of the inclination of the slots 7 it is caused to pass through the slots to the working face of the disk. Thus in whatever position the disk may be the abrasive material is supplied to it from the back uniformly and continuously.

In Fig. 1 I show the disk adapted to grind the edges of a pile of glass plates 10, which are held on a movable table 11. The shaft 4, on which the disk is mounted, is driven by a pulley 12 and has a spring end bearing 13, which enables the disk to yield backwardly somewhat when the plates or other articles to be ground are pressed against it. The spring 14 may be disconnected and the disk rendered unyielding when it is desired to true the articles to a given width.

In Fig. 2 I show a modified application of my invention, in which the disk is used for pulverizing sand or other abrasive for the purpose of fitting it for the grinding or smoothing of glass and like materials. In this case the rotary disk 2 is set opposite to a stationary companion disk 14, which is mounted upon a rod 15, having a spring 16, which presses it against the disk 2, and thus takes up the wear of both surfaces and supplies the pressure required for pulverizing. The rod 15 and the shaft 4 are lined, so that they are in exactly the same axial plane, and the grinding-faces of the disks 2 and 14 will therefore wear evenly and without grinding into each other, so as to form ridges, and thus destroy their efficiency. The disk 2 may be con-

structed as above described, except that the passages 5^a, as shown in Fig. 5, are short and do not extend to the periphery of the disk. The material to be pulverized is therefore fed near the axis of rotation and is forced outwardly between the faces of the disks 2^a and 14 by the centrifugal force of the rotating disk 2^a and is pulverized and discharged at the periphery in the desired powdered condition. A hood 17, provided with an exhaust-fan, may be placed around the disk to convey the pulverized material to a convenient receptacle.

In the modification of my invention shown in Figs. 7 and 8 the disk is provided with a peripheral grinding-surface, and the abrasive material is fed thereto through passages 5', constituted, preferably, by sector-plates D, spaced a slight distance apart and covered by a plate C'. The plates D preferably project somewhat beyond the peripheries of the plates B and C', and the periphery of the disk may be shaped as desired for the grinding of moldings or other curved or beveled shapes.

If desired, the shaft 4 may be extended through the cover-plate C', so as to afford a bearing on both sides of the disk, as indicated by dotted lines in Fig. 8.

Within the scope of my invention the construction of the apparatus may be modified. For example, the passages through the disk may be constituted otherwise than as above stated, and within the scope of my broader claims the abrasive material may be introduced through the hub or central part of the disk from the back thereof otherwise than by the spiral conveyer shown in the drawings.

I claim—

1. A grinding or polishing disk having passages extending outwardly in the same plane with the disk from its middle portion and communicating with the working face of the disk, and means adapted to introduce abrasive material at the back of the disk and at its middle portion; substantially as described.

2. A grinding or polishing disk having passages extending outwardly from its middle

portion in the same plane with the disk and communicating with the working face of the disk by inclined openings, and means adapted to introduce abrasive material at the back of the disk and at its middle portion; substantially as described.

3. A grinding or polishing disk having a rotary hub, a conveyer rotating with the hub, and passages leading therefrom outwardly in the disk and communicating with the working face; substantially as described.

4. A grinding or polishing disk having a rotary hub, a conveyer rotating with the hub, and passages leading therefrom outwardly in the disk and communicating with the working faces, and a stationary collar through which abrasive material can be introduced to the hub; substantially as described.

5. A grinding or polishing disk having passages extending outwardly from the central portion, and connected with slots in the working face, said passages being in communication with a conveyer situate in the back or opposite side of the disk and rotating therewith, whereby the abrasive material is fed from the back or opposite side to the grinding-surface; substantially as described.

6. A grinding or polishing disk having passages extending outwardly from the central portion and connected with inclined slots in the working face, said passages being in communication with a conveyer situate in the back or opposite side of the disk and rotating therewith, whereby the abrasive material is fed from the back or opposite side to the grinding-surface; substantially as described.

7. A rotary grinding or polishing disk set in an upright plane and having an inlet for abrasive material near its center, and having passages leading therefrom to the periphery; substantially as described.

In testimony whereof I have hereunto set my hand.

DANIEL J. MURNANE.
